UNITED STATES PATENT OFFICE.

WILLIAM A. STOLLEY, OF DOWAGIAC, MICHIGAN.

DESIGN FOR A FISH-BAIT BODY.

57,739.

Specification for Design.

Patented Apr. 26, 1921.

Application filed December 5, 1919. Serial No. 342,844. Term of patent 14 years.

To all whom it may concern:

Be it known that I, WILLIAM A. STOLLEY, a citizen of the United States, residing at Dowagiac, in the county of Cass, State of Michigan, have invented a new, original, and ornamental Design for a Fish-Bait Body, of which the following is a specification, reference being had to the accompanying drawing, forming a part thereof.

Figure I is a front perspective view of a fish bait body showing my new design;

Fig. II is a side elevation thereof; and Fig. III is a front elevation.

I claim:

The ornamental design for a fish bait body, as shown.

WILLIAM A. STOLLEY.
